(57) **CLAIM**

The ornamental design for a catamaran-style transport ship, as shown and described.

DESCRIPTION

FIG. 1 is a top view of a catamaran-style transport ship.

FIG. 2 is a bottom view thereof.

FIG. 3 is a right-side view thereof.

FIG. 4 is a left-side view thereof.

FIG. 5 is a front view thereof.

FIG. 6 is a rear view thereof; and,

FIG. 7 is an upper front-right isometric view thereof.

The broken lines represent portions of the catamaran-style transport ship that form no part of the claimed design.
